GARMENT

Eric L. Frank, Baltimore, Md.

Application November 24, 1941, Serial No. 420,260

4 Claims. (Cl. 2—94)

(Granted under the act of March 3, 1883, as amended April 30, 1928; 370 O. G. 757)

The invention described herein, if patented, may be manufactured and used by or for the Government for governmental purposes, without the payment to me of any royalty thereon.

This invention relates to improvements in wearing apparel and has particular reference to a garment adapted to be worn by military ski troops or mechanized troops or others who indulge in the sports of skiing or hunting.

Various types of garments have been proposed for the use of skiers and others, that would provide a simple, light and compact garment that would not be bulky, yet give adequate protection in severe weather, which is encountered when skiing.

A garment suitable for military ski troops has to have all these qualities and have the added qualities of having large pockets to carry the necessary equipment and odds and ends incidental to a soldier's existence in the winter climate.

Therefore, an object of the invention is to provide an improved garment of simple and practical construction, which is not bulky and will, by means of two pockets, supported by a web belt incorporated in the garment at the waist, to relieve all the strain from the back of the garment, provide means for carrying more than the usual necessities.

Another object of the invention is to provide a garment having a collar which can easily be adapted to be used as a hood, to protect the head and neck of the wearer when it is cold, and at other times present the usual appearance of an enlarged collar.

A further object of the invention is to provide an elastic insert at the waist of the garment to prevent snow from entering the space between the wearer and the garment, should the wearer fall in the snow.

A further object of the invention is to provide a closure of the slide-fastener type which is adapted to have an outer flap of the same material as the garment, completely covering the fastener, to prevent snow or ice from accumulating on the fastener, preventing its operation.

A further object of the invention is to provide a yoke on the garment which will prevent the moisture which accumulates on the outer surface of the yoke from penetrating into the garment.

With the above and other objects and advantages in view the invention consists of features of construction, arrangement and operation of

parts which will appear in the specification and be finally pointed out in the claims.

While the preferred embodiment of the invention is shown, it is to be understood that slight changes in the form and minor details of construction may be resorted to without departing from the spirit of the invention or falling beyond the scope of the claims.

Referring now to the drawings, in which similar characters and references in the several figures indicate identical parts:

Fig. 1 is a front elevation of the garment embodying the invention.

Fig. 2 is a rear elevation of the same.

Fig. 3 is a front elevation of the garment in open position.

Fig. 4 is a fragmentary sectional view along line 4—4 of Fig. 1.

Fig. 5 is an enlarged fragmentary view of one of the pockets.

Fig. 6 is a diagrammatic sectional view taken on the line 6—6 of Fig. 3.

Referring to the drawings by numeral, 10 is used to designate the garment in general, which in the present instance has been designed for the use of ski troops, but it should be understood that the present invention may be applied to any form of outer garment generally used for protection from the elements.

The garment 10, which is made of a light, water-repellant material, comprises the divided front body portion 11 and the back body portion 12, which are provided with the usual sleeves 13, having gussets at the armpits to allow greater freedom of movement. The garment is further provided with drawstrings 14 to adapt the waist of the garment to the individual.

A large collar or hood 15, lined with a light woolen material, or with double-texture material of the outer fabric, is attached to the neckline of the garment and by means of slide fastener 16 is adapted to normally extend downward over the back of the garment, in a smooth and flat condition. Drawstrings 17 are positioned within a sheath provided in the edge of the collar or hood 15 so that the opening of the hood around the face of the wearer can be restricted as to size.

The garment 10 is provided on the front body portions 11 with two pockets 18, having flaps 19, which are held closed by any well-known means, such as buttons 20.

A slide fastener 21 is provided to close the divided front portions 11 and there is also pro-

vided an outer flap 22 of the same material as the garment, which is adapted to cover the fastener 21 to prevent the fastener from becoming clogged with snow and ice and thus becoming inoperative. Straps 23 are provided at the lower end of the sleeves 13 and are adapted to be regulated to wrist size by means of buttons 24.

The present invention has been developed to provide a garment with two pockets 25, so situated with respect to the garment that the pockets can become invisible when the coat is being worn, during which time said pockets are empty, but when full will extend below the garment for convenience, in carrying numerous articles of equipment.

Entrance to the pockets 25 is gained by means of slide fasteners 26 which are positioned at the waist of the rear portion 12 of the garment 10.

A strip 27 of the same material as the garment is positioned in the center of the rear body portion of the garment and extends from the neckline to the bottom of the garment, thereby adding strength to the back portion 12.

A yoke 28 is positioned at the shoulders and is fastened to the garment at the neckline 29 and around the shoulders at 30. The points of the yoke in the front are secured in place by means of buttons 31. This construction permits the passage of air between the yoke and the garment, thus preventing the moisture which accumulates on the outer surface of the yoke from penetrating into the garment, since an evaporative action takes place prior to the actual absorption of the moisture.

Pockets are provided on the inside of the garment and are adapted to be closed by flaps 32 and buttons 33. The inner flap or lining 34 of the garment is gathered at the bottom and provided with an elastic thread so as to engage the wearer snugly and thus prevent snow from getting up under the jacket if the wearer falls into the snow.

One side of the pockets are attached to the body portion 12 by means of threads 25', while the other side of the pocket is secured to the flap or lining 34 by threads 33'. Loops 34' attached to the flap 34 are adapted to receive a web belt 36 so that the coat may be drawn tightly about the waist of the wearer. When the pockets are not in use, they may be folded so as to be retained in an upright invisible position by means of tabs 37 and buttons 38. The lining of these pockets can consist of a rubberized, light material to preserve the outer fabric from inside influence and to make these pockets easy to clean.

The pockets thus attached are carried as if they were part of the coat but since the weight of the pockets is wholly carried and supported by the web belt 36 and their disposition is determined in the manner previously described, a considerable weight can be more easily carried than if the pockets were directly supported by the garment itself in the usual manner.

Although the invention has been described in connection with a military ski garment it is not so limited, since numerous changes in details of construction and arrangement of parts may be effected without departing from the spirit of the invention and fall beyond the scope of the claims.

Having thus described the invention, what is claimed as new and desired to secure by Letters Patent is:

1. A garment comprising in combination a body portion, a pocket, one side of said pocket being attached to the rear of the body portion at the waist line thereof, said pocket being of a length to extend below the waist line of the body portion and freely suspended therefrom, and fastening means on said body portion adapted to engage fastening means on said pocket when said freely suspended portion of the pocket is folded upwardly so as to extend above the waist line of said body portion.

2. A garment comprising in combination a body portion, a pocket, one side of the pocket being attached to the waist line at the inside rear part of the body portion, said pocket being adapted to extend below the waist line of the body portion when in use, and means on the inside of the rear of the body portion for retaining a belt, said belt overlying and supporting the upper portion of the pocket.

3. A garment comprising in combination a body portion, a pocket, one side of said pocket being attached to the waist line at the inside rear part of the body portion, a lining attached to the opposite side of said pocket, and means on said lining for retaining a belt.

4. A garment comprising in combination a body portion, a pocket, one side of said pocket being attached to the waist line at the inside rear part of the body portion, said pocket being of a length to extend below the waist line of said body portion and freely suspended therefrom, a lining attached to the opposite side of said pocket above the middle portion of said pocket, and means comprising a separate body encircling member secured to said lining for supporting said pocket.
